UNITED STATES PATENT OFFICE.

ALICE J. WILSON, OF ABILENE, TEXAS.

DISH-DRIER.

SPECIFICATION forming part of Letters Patent No. 410,818, dated September 10, 1889.

Application filed October 9, 1888. Serial No. 287,697. (No model.)

To all whom it may concern:

Be it known that I, ALICE J. WILSON, of Abilene, in the county of Taylor and State of Texas, have invented a new and Improved 5 Dish-Drier, of which the following is a full, clear, and exact description.

Reference is to be had to the accompanying drawings, forming a part of this specification, in which similar letters of reference indicate 10 corresponding parts in all the figures.

Figure 1 is a perspective view of my new and improved device for drying dishes, knives, forks, spoons, &c. Fig. 2 is a sectional elevation of the same, and Fig. 3 is a sectional 15 plan view taken on line xx of Fig. 2.

The invention will first be described in connection with the drawings, and then pointed out in the claims.

The drier may be made of tin, galvanized 20 iron, or any other suitable material, and comprises the body A, (which is, by preference, circular and flaring,) the hinged lid or cover B, and the base C. In the base C or bottom of the body A is held a false bottom D, supported some distance from the bottom E by 25 the legs D' or the flange D², or both. The false bottom D is perforated and forms the chamber F, from which projects the spout G, by which the drainage-water may be poured 30 off from the chamber F below the false bottom D.

H is a curved projecting piece of sheet metal secured to the side of the body A to form a chamber H', into which knives, forks, 35 and spoons may be placed to drain and dry. The spout G is arranged at the outer surface of this projection, as shown, and the body A is perforated at H² to permit the water to pass from the chamber H' into the body A, and 40 thence through the perforated false bottom D to the chamber F.

J J are uprights attached to the upper sur-

face of the false bottom D, and which support the cross-pieces K, on which the dishes to be dried are placed, or against which they are 45 leaned.

The cover B is perforated to permit the escape of steam, and the drier is provided with a handle L, by which it and its contents may be conveniently handled. 50

The drier is to save the work of wiping dishes. The dishes are washed, turned down in the drier, and hot water poured over them. The lid or cover is then closed and the drier shaken a little to drain off the water, and the 55 heat remaining will dry them without further labor and with a better and glossier appearance than can be produced by wiping. The steam rising passes off through the perforations of the cover, and the drainage-water 60 may be poured out through the spout G.

Having thus described my invention, what I claim as new, and desire to secure by Letters Patent, is—

1. The dish-drier herein shown and de- 65 scribed, comprising the body A, cover B, false bottom D, side chamber H', and spout G, substantially as described.

2. The false bottom supported a short distance above the main bottom of the drier and 70 provided with the opposite uprights J J, in combination with the straight parallel cross-pieces K, held by the uprights J, substantially as shown and described.

3. The body A, having perforations H², and 75 having side projection H and spout G, in combination with the cover B, false bottom D, supported from the main bottom of the drier, and having the uprights J and cross-pieces K, substantially as described.

ALICE J. WILSON.
